UNITED STATES PATENT OFFICE.

FREDERICK E. WOODBURY, OF MILWAUKEE, WISCONSIN, AND BENJAMIN HARRIS AND CENTENNIAL HARRY BENEDICT, OF LAKE LINDEN, MICHIGAN; SAID HARRIS ASSIGNOR TO SAID WOODBURY AND BENEDICT.

APPARATUS FOR TREATING ORE.

No. 814,002.

Specification of Letters Patent.

Patented March 2, 1909.

Application filed April 2, 1902. Serial No. 101,111.

To all whom it may concern:

Be it known that we, FREDERICK E. WOODBURY, of the city and county of Milwaukee and State of Wisconsin, and BENJAMIN HARRIS and CENTENNIAL HARRY BENEDICT, of Lake Linden, in the county of Houghton and State of Michigan, citizens of the United States, have invented certain new and useful Improvements in Apparatus for Treating 10 Ore, of which the following is a specification, reference being had to the accompanying drawing, forming a part thereof.

Our invention relates to concentrating plants or apparatus for the treatment of ores 15 or metal bearing rock. Its main objects are to effect a more complete preliminary classification and separation of the concentrates and slimes from the gravel and sand or material requiring further treatment, as the 20 pulp or crushed ore or rock is discharged from the stamp or crusher; to obtain directly and immediately from the pulp as it comes from the crusher one or more finished products or grades of concentrates ready for 25 smelting; to reduce the volume of material requiring further treatment, after such preliminary classification and separation is made; to economize in apparatus required for such further treatment and thereby effect 30 a material saving of water, labor, time and space; to avoid dilution and consequent loss of slimes; and generally to improve the construction and operation and to increase the efficiency of apparatus for the preliminary 35 classification of ores and metal bearing rock.

It consists in certain novel features in the construction and arrangement of parts and in the combinations of parts hereinafter particularly described and pointed out in the 40 claims.

In the accompanying drawings like letters designate the same parts in the several figures.

45 Figure 1 is a vertical longitudinal section of an ore classifier and separator embodying an essential part of our invention; Fig. 2 is a plan view of the same partially broken away; Fig. 3 is a diagram or plan view on a reduced 50 scale showing the classifier and separator as connected with and arranged in relation to a stamp-mill or ore crusher and concentrating jigs to which a portion of the material is delivered for further treatment; and Fig. 4 is a

vertical cross section on an enlarged scale of 55 the upper part of the classifier and separator.

With apparatus heretofore generally used for treating ore of the kind to which this invention is particularly adapted, the ore as it comes from the crusher is first divided into a 60 number of equal and similar parts. Each of these parts is then subjected a number of times to the action of upward currents of water, the heavier particles in each classification falling through the upward current 65 and being delivered to jigs for further treatment, and the lighter particles or slimes being finally carried over the tail of the last separator. It is evident that in such a system a 70 large amount of water is required, and that most of this water is added to and dilutes the slimes. This necessitates large settling boxes with overflows, and results in great loss of fine mineral portions, before they are in proper condition for treatment by the apparatus usually employed for recovering slimes. 75

With the apparatus herein shown and described the slimes are taken off with little or no dilution, and the greater part of the concentrates are removed from the pulp as it 80 comes from the crusher by the preliminary classification. One or more finished products or grades of concentrates in condition for smelting are separated and removed from the sand, gravel or jiggling material requiring 85 further treatment. The slimes being separated and conducted off in this preliminary classification are not diluted by the addition of water required to grade or classify the pulp according to the old method and by the 90 further addition of water to that part of the pulp or to the jiggling material which requires further treatment. This is of prime importance, because the addition of water necessitates extra apparatus such as settling tanks, 95 employed in connection with the usual hydraulic separators to remove the surplus water from the slimes preparatory to their concentration on slime tables, and the separation of this surplus water carries off as 100 waste a large part of the fine, almost impalpable particles of which the slimes are composed, thus entailing more or less loss, according to the volume of additional water. Hence 105 a material saving in slimes, a reduction of apparatus required for further treatment, and a consequent saving of water and of labor required for the operation of such apparatus

are effected by this preliminary classification. The apparatus herein shown and described is designed to separate and remove from the pulp two grades of rich, heavy concentrates,—
 5 a fine grade or hutch work, which passes through the screen, and a coarser grade taken from the lower part of the jiggling bed on the screen,—and to separate from the sand and gravel requiring further treatment, slimes
 10 with a comparatively small volume of water from which they can be readily recovered with little loss.

Referring now to the drawing, *a* is a horizontally disposed screen arranged over a hutch
 15 *b* having an inclined bottom and one or more discharge openings *c*, and a water supply opening *d*. At one end of the screen the hutch communicates with a plunger compartment *e*, which extends above the screen
 20 and is provided with a reciprocating plunger *f* loosely fitted therein. The plunger *f* is provided with rods *g* extending upwardly through the top plate *h* and vent tubes *i*. The plunger rods *g* are connected with cranks,
 25 eccentrics or other means, not shown, for imparting a reciprocating movement to the plunger.

j is a vertically adjustable shield, which may be conveniently made of sheet metal
 30 bent into suitable form. It is secured by bolts *k* to a flanged plate *l*, attached to the tail plate *m*. The interior of said shield communicates through a horizontal slot or opening *n* in the plates *l* and *m* with a spout *o*, by which a part of the material passing
 35 underneath the shield is conducted therefrom for further treatment. The opening *n* is provided with a vertically adjustable gate or valve *p*, for regulating the flow of water carrying the sand and gravel from the interior of shield *j*. It may be adjusted and secured in place by means of a bolt *q* passing through the plate *l* and a slotted upward extension of said gate. *r* is another vertically
 40 adjustable shield arranged within the shield *j* and extending below it. It may be conveniently supported by means of slotted straps *s*, secured by bolts *t* to a cross bar *u*.

v is a rubber hose or flexible pipe leading
 45 from the interior of the shield *r* and vertically adjustable within said shield. It may be conveniently supported at its inlet end within the shield by a vertically adjustable rod *w*, secured by a bolt and thumb nut *x*, to the
 50 cross bar *u*.

y is a box or compartment extending across the tail end of the machine and having an opening *z* at one or each end for conducting off the tailings which overflow the tail plate *m*.

Referring to Fig. 3, illustrating the arrangement of the classifier and separator with relation to a stamp mill or ore crusher and jigs or concentrators, 2 designates a
 55 stamp mill, and 3, 3 two double jigs. The

pulp or crushed ore from the stamp mill is delivered by a suitable launder or conduit 4, upon the top plate *h* over the plunger compartment at the head end of the classifier. The discharge spout *o*, leading from the interior of the shield *j* at the tail end of the classifier, discharges into launders or conduits 5, 5, leading to the head ends of the jigs 3. The discharge openings *z* at the ends of the box *y* are connected by suitable conduits 6, with slime tables or other machines or apparatus for further treatment of the lighter material which flows over the tail plate *m* of the classifier.

In the operation of the machine, the material as it comes from the ore crusher 2, containing particles or pieces varying in size from slimes to coarse gravel, is fed over the plate *h* upon the screen *a*, and is subjected uniformly the entire width of the screen to the pulsations of water produced by the plunger *f*. The material is thus caused to arrange itself in layers according to the specific gravity of the particles, the fine heavy particles working downward and passing through the screen into the hutch *b*, from which they are removed through the openings *c*, and the light particles working upward. The material remaining on the screen is gradually advanced towards the tail end by the pulsating current of water. By the time it reaches the shield *j*, the lightest particles have assumed a position in the upper part of the bed, the heaviest particles a position next to the screen in the lower part of the bed, and particles of intermediate weights or specific gravities in layers or strata between the top and bottom of the bed. The fine light particles and slimes held by the pulsating current of water above the lower edge of the shield *j*, are carried around outside of said shield over the tail plate *m*, into the box *y*, from which they are conducted off through conduits 6, for further treatment on slime tables or other apparatus.

By varying the height of the tail plate *m*, the size of the largest particles entering into the slimes can be regulated. The heavier material occupying the intermediate portion of the bed and passing under the shield *j*, is subjected to the pulsating current of water as before, and the lighter particles occupying a position above the lower edge of the inner shield *r*, pass around it and are discharged through the opening *n* and spout *o*, into the launders 5, by which the sand and gravel are conducted to the jigs 3 for further treatment. The heavier particles, lying closer to the screen, pass under the shield *r* and are drawn off as a concentrate through the hose *v*. By varying the height of the intake end of this hose a body of concentrates of any desired depth can be maintained upon the screen to serve as a bed through which the finer particles or hutch-work have to pass.

This will serve alike when the desired concentrate is of the same material as the bed and when it is of different material. The height of the shield *r* with relation to the screen determining the grade or character of the material that can pass into it, by vertical adjustment of the shield mineral of any desired concentration may be discharged therefrom. The outer shield *j* must be adjusted to extend at its lower edge sufficiently into the upper part of the screen bed to prevent slimes from passing underneath and entering it with the gravel and sand. The slime separation is also regulated by the gate *p*, the area of the opening *n* determining the amount of water drawn from the screen through the shield *j*, and the amount overflowing the tail plate.

The amount of water discharged through the opening *n* must be sufficient to remove the gravel and sand, but must not be sufficient to draw from the supply which carries the ore to the screen; otherwise, slimes will be drawn off underneath and through the shield *j*, with the gravel and sand. When once the proper area of this opening *n* has been determined and adjusted by the operator, the machine requires no attention except as the quantity and quality of material treated may materially vary.

By means of the apparatus constructed and arranged as herein shown and described, a preliminary classification is made of pulp or crushed ore, into first, fine heavy concentrate or hutch-work; second, coarse heavy concentrate which is discharged continuously or intermittently; third, jiggling gravel and sand, or material requiring further treatment; fourth, slimes.

It will be apparent that by increasing the number of shields, the jiggling material or material requiring further treatment, and the concentrates, may be further subdivided, so that different kinds or grades of material may be delivered at the same time from the classifier. The amount of water required to operate this classifier and to separate and remove the slimes, is less than that required for the operation of any of the slime separators or pulp classifiers in general use, besides, a final concentration of ore is obtained and dilution and loss of slimes are avoided.

Various changes in details of construction and arrangement of parts may be made within the spirit and intended scope of the invention.

We claim:

1. In apparatus for treating ores the combination with a crusher and a concentrator, of an intermediate classifying jig comprising a screen and means for producing pulsations of water through the screen and provided with a plurality of discharges above the screen, including a slimes discharge, a cen-

trates discharge and a discharge for material requiring further treatment, means for restricting the volume of water passing out with the slimes, a conduit leading from the discharge for material requiring further treatment to the concentrator, and a conduit from the crusher to the classifying jig, substantially as described. 70

2. In apparatus for treating ores the combination with a crusher and a concentrator, 75 of an intermediate classifying jig comprising a screen and means for producing pulsations of water through the screen and provided with a plurality of discharges above the screen, including a slimes discharge 80 and a discharge for material requiring further treatment, and with means for restricting the volume of water passing out with the slimes, a conduit leading from the discharge for material requiring further treatment to the concentrator, and a conduit from the crusher to the classifying jig, substantially as described. 85

3. In apparatus for treating ore the combination with a crusher and a concentrator, 90 of an intermediate classifying jig comprising a screen and means for producing pulsations of water through the screen and provided with a tail plate extending above the screen, a shield terminating at its lower edge below the top of the tail plate, a discharge conduit for slimes which pass over the tail plate and means for restricting the volume of water passing out with the slimes, a conduit for material requiring further treatment leading from said shield to the concentrator and a conduit from the crusher to the classifying jig, substantially as described. 95

4. In apparatus for treating ore the combination with a crusher and a concentrator, 105 of an intermediate classifying jig comprising a screen and means for producing pulsations of water through the screen, and provided with a tail plate extending above the 110 screen, a vertically adjustable shield terminating at its lower edge below the top of the tail plate and above the screen, a discharge conduit for slimes which pass over the tail plate and means for restricting the volume 115 of water passing out with the slimes, comprising a valve for adjusting the discharge from said shield; a conduit for material requiring further treatment leading from said shield to the concentrator, and a conduit from the crusher to the classifying jig, substantially as described. 120

5. In apparatus for treating ore the combination with a crusher and a concentrator, 125 of a classifying jig comprising a screen and means for producing pulsations of water through the screen and provided with a tail plate extending above the screen, shields terminating at their lower edges at different levels below the top of the tail plate and above 130

the screen, a discharge conduit for slimes which pass over the tail plate and means for restricting the volume of water passing out with the slimes, a conduit for material requiring further treatment leading from one shield to the concentrator, a discharge conduit for concentrates leading from the other shield, and a conduit from the crusher to the classifying jig, substantially as described.

10. 6. In apparatus for treating ore the combination with a crusher and a concentrator, of a classifying jig comprising a screen and means for producing pulsations of water through the screen and provided with a tail plate extending above the screen, vertically adjustable shields terminating at their lower edges at different levels below the top of the tail plate and above the screen, a discharge conduit for slimes which pass over the tail plate and means for restricting the volume of water passing out with the slimes, a conduit for material requiring further treatment leading from the higher shield to the concentrator, a discharge conduit for concentrates leading from the lower shield and a conduit from the crusher to the classifying jig, substantially as described.

7. In apparatus for treating ore the combination with a crusher and a concentrator, of a classifying jig comprising a screen and means for producing pulsating currents of water through the screen and provided with a tail plate extending above the screen, vertically adjustable shields terminating at their lower edges at different levels below the top of the tail plate and above the screen, a discharge conduit for slimes which pass over the tail plate and means for restricting the volume of water passing out with the slimes, comprising a valve for adjusting the discharge from said shield; a conduit for material requiring further treatment leading from the higher shield to the concentrator, a discharge conduit leading from the lower shield and having a vertically adjustable inlet within said shield, and a conduit from the crusher to the classifying jig, substantially as described.

8. In apparatus for treating ore the combination with a crusher and a concentrator, of a classifying jig comprising a screen and means for producing pulsations of water through the screen and provided with a tail plate extending above the screen and with shields arranged one within the other with their lower edges at different levels below the top of the tail plate and above the screen, a discharge conduit for slimes which pass over

the tail plate, a discharge conduit for material requiring further treatment leading from the space between the shields to the concentrator, a discharge conduit for concentrates leading from the inner shield, and a conduit from the crusher to the classifying jig, substantially as described.

9. In apparatus for treating ore the combination of a screen, a hutch surrounding and extending above the screen and provided above the screen with an overflow for light, floating or suspended material, and at a level below that of the overflow with a submerged discharge, a shield interposed between said discharge and overflow and extending below the overflow, means of restricting the flow of material through said discharge from the space cut off by said shield, a second shield located within said space, extending below the first shield and forming an inclosure for concentrates, a discharge conduit for concentrates leading from said inclosure, a water supply connection leading into the hutch and adapted to produce an upward current through the screen and the jigging bed thereon, and means for producing pulsations of the water through the screen and jigging bed, substantially as described.

10. In apparatus for treating ore the combination of a screen, a hutch surrounding and extending above the screen and provided above the screen with an overflow and at a level below the overflow with a submerged discharge, a shield interposed between said discharge and overflow and extending below the overflow, a shield within the space cut off by the other shield, a discharge conduit having a vertically adjustable inlet within the space cut off by the inner shield, a water supply connection leading into the hutch, and means for producing pulsations of water through the screen and the jigging bed thereon, substantially as described.

In witness whereof, we hereto affix our signatures in presence of two witnesses.
